HYDRAULICALLY OPERATED WORK DISPOSING TABLE

Roy F. Dehn, Wickliffe, Ohio, assignor to The Cleveland Crane & Engineering Company, Wickliffe, Ohio, a corporation of Ohio

Application March 29, 1957, Serial No. 649,555

2 Claims. (Cl. 83—373)

The present invention relates to a sheet cutting apparatus and, more particularly, to a shear press having a table for supporting a section of the sheet material.

An important object of the present invention is the provision of a new and improved shear press having a movable knife, a gauge member displaced to one side of the knife and against which the length of material to be severed is measured, and a table for supporting the material extending from the knife to the gauge member to facilitate the accurate gauging and shearing of sheet material to be severed into sections, particularly sheet material sufficiently thin as to bend or flex if not supported substantially throughout its length, the shear being so constructed and arranged that the table is moved with the knife, when a severing operation occurs, to prevent undue distortion of sheet material from a gauging position to a position where the severed material thereon is dischargeable past the gauge member and is maintained in this position for a length of time sufficient to permit the severed material to be discharged past the gauge member.

Another object of the present invention is the provision of a new and improved shear press having a fixed knife and a cooperating movable knife displaced to one side of the fixed knife, a table for supporting sheet material on the one side of the fixed knife, and fluid pressure responsive means for holding the table in a position for supporting material level with the fixed knife and for moving the table, upon actuation of the movable knife, to a deflected position to prevent undue distortion of the sheet material.

Another object of the present invention is the provision of a new and improved shear press having a movable knife actuatable to perform a severing operation, a table for supporting material extending to one side of the knife, and a gauge member adjacent the top of the table against which the extending material is abutted to gauge the length of material to be severed, the press being so constructed and arranged that the portion of the table supporting the material during the gauging operation is movable and is normally held in a gauging position and upon actuation of the severing mechanism is moved to a position where the severed material thereon is dischargeable past the gauge member and is returned to gauging position after a predetermined time, the movements of the table being controlled by fluid pressure actuated mechanism and the table preferably including power driven rollers actuated when a severing operation occurs to discharge the severed material past the gauge member and from the table.

The invention resides in certain constructions, combinations and arrangement of parts and further objects and advantages will be apparent to those skilled in the art to which it relates from the following description of the preferred embodiment described with reference to the accompanying drawings forming a part of this specification, in which:

Fig. 1 is a side elevational view of a shear press embodying the present invention;

2

Fig. 2 is a perspective view showing the back of the press of Fig. 1 with the table omitted;

Fig. 3 is a fragmentary vertical sectional view through the press of Fig. 1;

5 Fig. 4 is a view taken approximately along line 3—3 of Fig. 3;

Fig. 5 is a fragmentary sectional view taken approximately along line 5—5 of Fig. 3; and

Fig. 6 is a simplified electrical diagram showing a portion of the control circuit for the press.

While the present invention is susceptible of various modifications and constructions and of uses with various types of sheet cutting apparatus, it is herein shown and embodied in a shear press of the type shown in Patent 2,759,582 to Roy F. Dehn. Since the shear shown herein is similar to the shear shown and described in the aforesaid patent, only those parts of the shear which are necessary to a complete understanding of the present invention are herein shown and described in detail and reference is made to the aforesaid patent for a complete showing and description of the other parts of the shear.

Referring to the drawings, the reference character A designates a frame comprising stress-resisting, plate-like end members or side housings 10, 11 having aligned

25 openings 12, in their front edges, a crown 14, and a bed comprising plate-like members 15, 16, 17, the latter of which forms a scrap chute. The vertical plate-like member 15 is located immediately to the rear of and welded to the horizontal plate-like member 16, which member in addition to reinforcing the upper edge of the member 5, forms a support or work table for the work. The upper member or crown 14 is generally box-shaped in cross section and has its opposite ends welded to the side housings 10, 11 adjacent to their front upper edges. Web members 20, 21, 22 welded to the interior of the member 14 reinforce the same and the lower ends of the members 20, 21 which extend below the rear side of the member 14 form supports for suitable bearings within which a crankshaft 23 is rotatably supported.

40 The shearing operation is performed by a stationary shearing knife 24 located in a cut-out portion at the upper rear corner of the bed and a movable shearing knife 25 connected to the lower front edge of a movable ram or blade, designated generally by the reference character B.

45 The movable ram or upper blade B which extends substantially from one side of the housing to the other is of built-up construction and comprises a longitudinally extending front plate 26 welded to the front ends of rearwardly extending end members 27, 28, the rear ends of which are rotatably connected to short, shaft-like members 30, 31 rotatably supported in suitable apertures in the side housings 10, 11 respectively, for rotation about an axis eccentric to the axis about which the end members 27, 28 are rotatable. The axis about which the ram or blade B is pivoted is preferably slightly above the plane of the work supporting surface of the bed.

50 In addition to the front plate 26 and the end members or plates 27, 28, the upper blade or ram B comprises a plate 32 extending between and welded to the end members 27, 28 and a bottom plate 33 having an upwardly extending rear flange 34. The front edge of the bottom plate 33 abuts against and is welded to the rear side of the plate 32 adjacent to the lower edge thereof and the ends of the bottom plate are welded to the end members 27, 28.

55 The front plate 26 of the blade B is inclined at a slight angle to the vertical, as clearly shown in Fig. 1, to provide clearance between the ram or blade B and the stationary knife when the blade is oscillated. The lower front edge of the plate 26 is cut out so as to receive the upper shearing knife 25, which knife is held in position therein by a plurality of screws. The lower edge

70

of the plate 26 is inclined lengthwise so that the knives will effect a true shearing action.

The front end of the ram or movable blade B is supported and the entire blade assembly is adapted to be oscillated about the shafts 30, 31 by pitmans 46, 47, the upper ends of which are operatively connected to eccentrics on the crankshaft 23. The lower ends of the pitmans are connected to short shafts fixed in opposite ends of the blade B. The rotation of the crankshaft 23 is effected and controlled to reciprocate the ram or blade B in one or more complete shearing strokes by an electric motor 48 adjustably secured to the back of the crown 14 and operatively connected to the crankshaft by means including a clutch which is controlled in synchronism with a brake mechanism in such a manner, as will be presently described, that when the operating pedal 50 of an electric control switch 51 is depressed and immediately released, the crankshaft makes one complete revolution but will continue to rotate as long as the pedal is depressed. As shown, the weight of the movable blade B is counterbalanced by adjustable compression springs, one at either end of the ram, located within tubular housings 52, 53 fixed to the crown member 14.

The shears shown also include a plurality of spring-loaded, hold-down devices 54 detachably bolted to the lower edge of a hold-down plate 55 suspended from the forward arms of bell crank levers 56, only one of which appears in the drawings, the rear arms of which levers are provided with rollers adapted to engage cams on the crankshaft 23. The levers 56 are continuously urged in a clockwise direction, as viewed in Fig. 1, to engage the rollers thereon with the cams on the crankshaft by suitable compression springs 58 interposed therebetween and the top of the crown member 14.

The rotor shaft of the motor 48 is connected by a flexible drive connection designated generally as 61 to a grooved pulley or flywheel 63 rotatably supported on a shaft 64, which shaft is in turn rotatably supported in suitable bearings fixed to the side housing 10 and to a plate 65 spaced therefrom but connected thereto by an irregularly shaped plate 66 interposed therebetween and the side housing 10. The plates just mentioned form an enclosure or compartment on the outside of the side housing 10 which houses mechanism including a pinion gear 67 keyed to the shaft 64 and in mesh with a large gear 68 keyed to the end of the crankshaft 23.

The flywheel 63, which is driven continuously by the motor 48, is journaled on shaft 64 by anti-friction bearings 69 which provide free relative rotation between the flywheel and shaft, and the flywheel is adapted to be connected and disconnected with the shaft 64 from which the crankshaft 23 is rotated and the movable blade B oscillated by a power friction disk clutch designated generally by the reference character 70.

The clutch 70 is a spring released, fluid pressure actuated clutch with the pressure fluid being supplied thereto through a conduit 71 connected to a bore in the shaft 64 which leads to a piston member actuated to engage the clutch when fluid pressure is supplied thereto. The pressure fluid supplied through the conduit 71 also actuates a brake mechanism 72 for holding the shaft 64 against rotation to a released position. The brake mechanism 72 is located on the shaft 64 outwardly of the end member 10 and is spring biased to an engaged position to prevent rotation of the shaft and is actuated to a disengaged position to allow rotation of shaft 64 and, in turn, the rotation of crankshaft 23, when pressure fluid is supplied through the conduit 71. The supply of fluid pressure is under the control of the operating pedal 50 of the electric control switch 51, and when the pedal is depressed, pressure fluid is supplied to the brake and clutch mechanism to respectively release and engage the mechanisms. When the pedal is depressed and released, a circuit is completed through a limit switch 75 to operate a solenoid valve 76 to supply pressure fluid

to the clutch and brake mechanism until the switch 75 is opened. The switch 75 is opened once during each revolution of the crankshaft 23 and therefore the clutch will be disengaged and the brake engaged after the crankshaft has made one complete revolution unless the pedal is maintained depressed. The control circuit will be described in more detail hereinafter.

The material to be severed is fed between the knives 24, 25 and the portion of the material in front of the knives is supported on the member 16 of the press bed while the portion extending rearwardly of the knives and between the end plates 10, 11 is supported by a table 77. The table 77 is disposed between the end members 10, 11 and extends from a point adjacent the movable knives 25 to the rear of the press, the top of the table being disposed at the level of the bed member 16.

A gauge mechanism C for gauging the section of material to be severed is carried by the flange 34 of the plate 33 of the ram and is disposed immediately above the table 77. The gauge mechanism includes a gauge member 81 extending parallel to the knife and is adjustable toward and away from the knives 24, 25 by the operation of a hand crank 82 fixed to one end of a shaft 83 supported by the ram B and extending transversely of the press. The shaft 83 is operatively connected to a pair of parallel lead screws 84, see Fig. 5, to rotate the latter upon rotation of the shaft 83 by the handcrank. The lead screws 84 extend perpendicularly to the knives 24, 25 and rotation thereof causes the movement of carriage blocks 85 which support the gauge member 81. The carriage blocks move toward or away from the knives and are guided in their movement by slides 86 supported at their forward ends on the shaft 82 for angular movement with respect thereto and at their rearward ends by linkages 87 connected at one of their ends to the flange 34. A bar 88 interconnects the linkages 87 and is operable to raise the rearward end of the gauge mechanism to lift the gauge member 81. The gauge mechanism is not described or shown in detail since it is substantially the same as that shown and described in Dehn Patent 2,520,495 and reference is made thereto for those details of construction and operation not shown or described herein. Suffice it to say that the gauge member 81 is adjustable toward and away from the knives 24, 25 to determine the length of the severed section, the material to be severed being fed from the bed member 16 past and between the knives 24, 25 and against the gauge member 81 prior to the severing stroke. The table 77 supports the section of material between the stationary knife 24 and the gauge 81 and facilitates the gauging of material which would normally flex or bend under its own weight.

The table 77 is comprised of a plurality of transverse rollers 90 supported between spaced side plates 91, 92. The upper peripheries of the rollers define a horizontal table surface at the level of the upper edge of the stationary knife 24 and each of the rollers is provided with a shaft 93 which is journaled at its opposite ends in the side plates 91, 92 and which extends outwardly of the side plate 91. The outer end of each of the shafts 93 has a sprocket 94 fixed thereto, the sprockets 94 meshing with a drive chain 95 driven in a manner described hereinafter.

The side plates 91, 92 are supported at their ends remote from the knives 24, 25 by a shaft 96 and are movable angularly about the shaft. The shaft 96 is part of a movable stand that comprises spaced vertical plates 97, 98 which support the shaft 96 and which are disposed outwardly of the side plates 91, 92 respectively and are mounted on a base plate 100. The base plate 10 is mounted on wheels and supports a motor 101 for driving the chain 95 to rotate the rollers 90. The motor 101 has its rotor shaft connected to the chain 95 through a fluid coupling 102. The fluid coupling 102 includes an output shaft 103 operatively connected by a belt drive 105 to drive a sleeve 106 rotatably supported on the shaft 96

outwardly of the vertical plate 97. The sleeve 106, in turn, is connected by a belt drive 108 to drive the shaft 93 of the end roller 90 adjacent the shaft 96. The described drive to the rollers 90 permits the rollers and the side plates 91, 92 to be moved about the axis of shaft 96 without interfering with the drive to the chain 95 since the sleeve 106 which functions as the driven member of the belt drive 108 also rotates about the axis of shaft 96.

The rollers 90 are normally held in a gauging position where the tops thereof define a table level with the knife 24 by a fluid pressure cylinder element 110 having a cylinder chamber member 111 pivotally connected to a lug 112 on the base plate 100 and a piston rod 113 pivotally connected at its outer end to the movable table. The cylinder element 110 is of the double acting type and has a conduit 115 for communicating with the cylinder chamber on one side of the piston, the upper side thereof as the cylinder is viewed in Fig. 3, and a conduit 116 communicating with the cylinder chamber on the other side of the piston. When pressure fluid is supplied to the cylinder through conduit 116 and the conduit 115 connected to drain, the piston therein moves upwardly to raise the table to its position for supporting material being gauged against the gauge member 81 and when the conduit 116 is connected to drain the end of the table adjacent the knife 24 will drop and the table will angularly move around the axis of shaft 96. The dropping of the table may be effected by the weight thereof but preferably fluid pressure is supplied through the conduit 115. In addition to fluid pressure and the weight of the table, the movable ram B may engage the end of the table adjacent the knife 24 to deflect the same as the blade moves downwardly.

The deflecting position of the table is shown in dot-dash lines in Fig. 3 and the table is in one mode of operation of the illustrated machine, maintained in this position, after a severing operation has occurred a period of time sufficient to permit the section of severed material thereon to move past the gauge member 81.

The connection of the cylinder 110 to the source of pressure fluid and to drain and the energization of motor 101 to rotate the rollers 90 are effected in a predetermined relationship to the movement of the knife 25 through its shearing structure.

The operation of the table 77 is under the control of the pedal 59 and a selector switch 120 located on the machine in an accessible spot and shown on the circuit diagram of Fig. 6. The selector switch 120 is, in the illustrated machine, a four-position switch having the following position: "Off, Automatic Discharge, Trim and Return Feed," designated respectively by the reference characters O, D, E, and F. When the selector switch is in the Automatic Discharge D position, depression of the pedal 59 will cause the movable knife 25 to be actuated through a single stroke and simultaneously with the actuation of the knife, fluid pressure is supplied to the cylinder chamber member 111 through the conduit 115 and the conduit 116 is connected to drain, causing the cylinder element to operate to drop the table 77 to its discharge position. The circuit for controlling the supply of fluid pressure to the cylinder element 110 includes a time delay relay shown in the circuit diagram of Fig. 6 which functions to maintain the table 77 in a depressed position for a predetermined length of time after its de-energization to enable the rollers 70 to discharge the severed section of material thereon past the gauge member 81. After this period of time, fluid pressure is supplied to the cylinder element 110 through the conduit 116 to cause the table to return to its horizontal gauging position where it is level with the bed member 116. Interlocking means is preferably provided to prevent a subsequent actuation of the shear prior to the return of the table 77.

When the selector switch is set in its "Trim" position E, depression of the pedal 59 will actuate the movable blade 25 through a single stroke, simultaneously drop the

table and start the rollers 90, and return the table immediately upon the completion of the severing stroke. In the "Return Feed" position F of the selector switch, the table is dropped with each shearing stroke and immediately returned and the power driven rollers 90 are operable in a reverse direction to move material thereon toward the knives 24, 25 when the table is in its horizontal position by the actuation of a switch 123. With the selector in its F position and with the back gauge disposed in a rearward position and lifted, material may be fed by power from the back of the press against a front stop.

A simplified control circuit for the shear is shown in Fig. 5 and the pedal operated switch 51, the limit switch 75, the selector switch 120, and the roller reversing switch 123 are shown schematically therein. Referring to Fig. 5, it will be seen that when the selector switch 120 is in its automatic discharge position D, the actuation of the foot pedal switch 51 completes a circuit to energize a relay FP having normally open contacts FP1, FP2, FP3, FP4. The contacts FP1 complete a holding circuit through the limit switch 75 to maintain the relay FP energized until the limit switch 75 is opened upon the completion of a single revolution of the crankshaft in response to the actuation of the switch 51. The contacts FP2, FP3, FP4 of the relay FP are respectively in circuit for energizing relays AD, T, and LG, and when closed complete a circuit to the respective relay provided the selector switch 120 is set in a position conditioning the relay for energization. Assuming that the selector switch is set in its "Automatic Discharge" position, the actuation of relay FP energizes the AD relay to close its normally open contacts AD1, AD2. The contacts AD1 complete a circuit for energizing the solenoid valve 76 for supplying pressure fluid to engage the clutch mechanism of the press and maintains the supply of pressure fluid as long as the relay AD is energized. The closing of the contacts AD2 upon actuation of the relay AD completes a circuit for energizing a relay TD which picks up immediately upon energization but which drops out only after a predetermined time after de-energization. The relay TD has normally open contacts TD1, TD2, which are closed when the relay is actuated, and which respectively complete circuits for causing the operation of the table 77 and of the rollers 90 in a forward direction. The contacts TD1 are in series with a solenoid valve 125 for controlling the supply of air to the cylinder element 110 and when the latter is energized fluid pressure is supplied to the element through conduit 115 and the conduit 116 connected to drain while, when the solenoid valve is de-energized, the connections are reversed. The solenoid valve may be one of any of the commercially available valves which will operate in the manner described and therefore is not herein shown or described in detail. The contacts TD2 of the relay TD are in series with and complete a circuit upon their closing for energizing a motor control relay 126 which effects operation of the motor 101 in a forward direction.

From the circuit as thus far described, it may be seen that when the selector switch 120 is in its "Automatic Discharge" position D and the foot pedal switch 51 actuated, the movable blade 25 is actuated through a severing stroke, the motor 101 is started and rotates the rollers 90 in a forward direction to discharge severed material, and the table 77 is dropped to a discharge position and returned with a predetermined time delay. It will be noted that a holding circuit is completed as soon as the crankshaft moves sufficiently to actuate the limit switch 75 to a closed position and at this time the foot pedal switch 51 can be released. Upon release of the foot pedal switch 51 the operation of the shear is under the control of the limit switch 75 and when the latter is subsequently again opened the crankshaft is disconnected from the movable blade and the relay TD is de-energized and opens after a predetermined time delay to break the cir-

cuits for energizing the forward relay 126 for the motor 101 and the solenoid valve for supplying pressure fluid to the cylinder element 110 through the conduit 115. The time delay in the operation of the relay TD is such that the rollers 90 will have sufficient time to cause the discharge of severed material thereon past the gauge member 81 before the table 77 is returned to its horizontal gauging position and the rollers 99 stopped.

When the selector switch 120 is in its "Trim" position E the relay T is energized upon the operation of the pedal switch 51 to actuate the relay FP. The energization of relay T closes its normally open contacts T1, T2, to respectively energize the solenoid valve 76 for actuating the movable blade 25 and the solenoid valve 125 for operating pressure fluid to the cylinder element 110 to cause the table to drop to its discharge position. When the holding circuit for the relay FP is broken the solenoid valve for the table 77 and the solenoid for the shear will be immediately moved to the de-energized position to stop the crankshaft rotation after one revolution and to return the table 77 to its horizontal gauging position.

When the selector switch 120 is in its "Return Feed" position F, the closing of relay FP in response to actuation of the pedal switch 51 causes energization of relay LG having normally open contacts LG1, LG2 and LG3. The closing of the normally open contacts LG1 energizes the solenoid valve 76 for actuating the shear, and the closing of the contacts LG2 causes the energization of the solenoid valve 125 to drop the table. When the selector switch is in its "Return Feed" position, the circuit is arranged so that the rollers 90 may be operated in a reverse direction whenever the table 77 is in its horizontal gauging position. The control for actuating the motor 101 in its reverse direction includes a reverse relay 130 and a circuit for energizing the latter, including a table limit switch 131 which is closed when the table is in its horizontal gauging position, the push button switch 123 and the normally open contacts LG3, connected in series. It can be seen from the circuit that if the relay LG is energized to close the contacts LG3 and the table 77 is in a horizontal position wherein the limit switch 131 is closed, the switch 123 may be actuated to energize the motor 101 to operate the rollers in a reverse direction.

Preferably the control circuit is arranged in such a manner that the movable knife cannot be actuated a second time, when the selector switch is in its Automatic Discharge position, until the table 77 is returned. To this end, the relay TD is provided with normally closed contacts TD3 which are connected in series with the pedal switch 51. The contacts TD3 render the switch 51 ineffective as long as the TD relay is in an actuated position.

It is also to be noted that the table 77 extends to a point where it is in the path of the blade B and that it is necessary to deflect the table to permit the severing operation, regardless of whether or not the severed material is to be discharged past the gauge member 81.

It can now be seen that the present invention provides a new and improved shear press which is extremely flexible and which includes a table for supporting material extending between the knives of the shear on one hand and a gauge member on the other, and which supports the material being gauged to prevent the flexing thereof. The table is so constructed and arranged that when the shear is actuated to sever the gauged section of material, the table is moved with the movable knife to support the material during the cut and is dropped to a discharge position

where the material thereon may be discharged past the gauge member. The table is maintained in the discharge position for a sufficient length of time to permit the material to be discharged and is then returned to a gauging position where, in the illustrated embodiment, it is on a level with the bed of the shear. The control circuit for the illustrated shear is so arranged that the shear cannot be actuated, when the circuit is conditioned for operation in an automatic manner, until the table has been returned. Furthermore, the circuit is so arranged that the shear may be selectively operated as a back feed shear or to the trim severed sheets.

While the preferred form of the invention has been described in considerable detail, it will be apparent that the invention is not limited to the constructions shown or the uses referred to and it is my intention to cover hereby all adaptations, modifications, and changes which come within the practice of those skilled in the art to which the invention relates and the scope of the appended claims.

Having thus described my invention, I claim:

1. In a shear press having a fixed knife and a cooperating movable knife displaced to one side of said fixed knife, power means for actuating said movable knife through a shearing stroke to sever sheet material, a material supporting table at said one side of said fixed knife, said table having one end disposed adjacent to said knives, pivot means for supporting the end of said table remote from the fixed knife for angular movement about an axis generally parallel with the fixed knife, means for normally maintaining said one end of said table substantially level with said fixed knife to support the material, and means operable to control said power means to effect a shearing stroke and for automatically controlling the last named means to cause said one end of said table to drop below said fixed knife to permit completion of the shearing stroke with a minimum distortion of said material.

2. In a shear press having a fixed knife and a cooperating movable knife displaced to one side of said fixed knife and connected to a ram or blade member oscillatable about an axis generally parallel with the length of the fixed knife and displaced to said one side of said fixed knife, power means for actuating said movable knife through a shearing stroke to sever sheet material, a gauge member disposed to said one side of said stationary knife and against which the material to be severed may be abutted to determine the length of the section severed upon actuation of said movable knife, a material supporting table at said one side of said fixed knife, said table having one end disposed adjacent to said knives, pivot means for supporting the end of said table remote from said fixed knife for angular movement about an axis generally parallel with said fixed knife, means for normally maintaining said one end of said table substantially level with said fixed knife to support the material, and means operable to control said power means to effect a shearing stroke and for automatically controlling the last named means to cause said one end of said table to drop below said fixed knife to permit completion of the shearing stroke with a minimum distortion of said material.
